METHOD OF WEAVING LADDER TAPES

Elbridge R. Holmes, Worcester, Mass., assignor to
Crompton & Knowles Loom Works, Worcester,
Mass., a corporation of Massachusetts

Original application March 16, 1942, Serial No.
434,920. Divided and this application August
24, 1942, Serial No. 455,828

5 Claims. (Cl. 139—22)

This is a division of my co-pending application Serial No. 434,920, filed March 16, 1942, for Loom for weaving ladder tapes.

This invention relates to improvements in looms for weaving ladder tapes such for instance as are utilized to support the cross slats of Venetian window shades and it is the general object of the invention to provide improved means for manipulating the warp threads which pass from one web to the other to form the ladder or crossing bars.

Ladder tapes customarily employ two webs which are connected at spaced intervals either by narrow groups of warp threads or woven sections. The warp threads which form the crossing bars are woven into the two webs between crossings, forming part of the sheds of their respective webs. When the point in weaving is reached at which a crossing bar is to be formed, the crossing warps leave the sheds in which they have been previously located and pass to the opposite web. The two sets of crossing threads cross each other at a point considerably behind the fells of the two webs and cause objectionable loops at the selvage of the webs at beat-up. It is an important object of my present invention to provide an advancing hook or the like for the crossing webs to move them to their extreme forward position prior to beat-up and preferably at a time in the advance of the lay when the weft threads will still be under sufficient tension to move to their respective fells without forming loops.

In previous looms for weaving ladder tapes it has been proposed to move the crossing warps forwardly by mechanism connected to the lay with the result in certain instances that the crossing threads do not move to their extreme forward position until after the harnesses have started to cross. Any loop which might have been formed at the selvage cannot therefore be straightened because the weft thread is held by the warp threads. It is another object of my present invention to provide means to advance the crossing warps to their extreme forward position prior to closing of the warp sheds and therefore permit the weft tension to straighten the aforesaid loops.

The warp sheds are ordinarily closed at front center but the exact time of closing depends upon the type of harness mechanism employed and also its setting. The sheds will always be partly open when the lay is at bottom center and it is a more specific object of my present invention to manipulate the crossing warp advancing means so that

it will reach its extreme forward position approximately at the time the lay is at bottom center. This timing insures that the sheds will be open enough to permit the weft tension to straighten the loops at the selvages.

The warp sheds are sufficiently open at top center to permit entry of the shuttles and on crossing beats of the loom the crossing warps will form a shed wide enough for entry of the advancing hook or the like before the lay reaches back center. In order that the crossing warp advancing means may reach its extreme forward position prior to front center it is a further object of my invention to move the crossing warp hooks or the like to their extreme rearward position at some point in the loom cycle between top and back centers and thereafter move the hook forwardly before the lay starts to advance. In this manner I give the crossing warp advancing hook its complete back and forth movements in a period considerably less than one full pick of the loom.

It is a specific object of my present invention to achieve the last named object by rack and pinion mechanism operatively connected to a transverse bar and effective starting at a point substantially at front center to cause the bar to move to its rearward position in a period something less than half a pick and immediately thereafter move the bar forwardly while the lay is still receding. The driving rack is caused to reciprocate by cam mechanism similar to that already known and the crossing warp advancing hook, pivotally mounted on the bar, is caused to swing laterally away from the warp threads as the bar moves rearwardly and then return to its normal position with respect to the bar behind the crossed warps as the bar starts forwardly. A further specific object of my invention is to provide improved cam means for rocking the crossing warp hooks on the bar during backward motion of the latter without disturbing the hooks as they move forwardly.

My invention further relates to an improved method for the manipulation of the warps in a loom weaving ladder tapes or the like. The method consists essentially in the steps of crossing the ladder forming warps, moving their point of crossing forwardly to cause the crossing warps to lie in the outside sheds of the ground fabrics while the ground sheds are open, exerting tension on the weft threads to take up slack at the selvages and thereby prevent formation of the loops while the ground sheds are open and thereafter closing the ground sheds.

With these and other objects in view which will appear as the description proceeds, my in-

vention resides in the combination and arrangement of parts hereinafter described and set forth.

In the accompanying drawings, wherein a convenient embodiment of my invention is set forth,

Fig. 1 is a vertical longitudinal section through a loom for weaving ladder tapes and having my invention applied thereto.

Fig. 2 is an enlarged plan looking in the direction of arrow 2, Fig. 1 and showing a hook and its operating mechanism in the normal position during non-crossing weaving operations of the loom.

Fig. 3 is a view similar to Fig. 2, but showing the crossing warp hook in the process of being moved to a position behind the crossing warps.

Fig. 4 is a vertical section on line 4-4 of Fig. 3 on an enlarged scale showing the cam which operates the crossing warp hook.

Fig. 5 is a vertical section on line 5-5 of Fig. 2 on an enlarged scale showing the rack and pinion mechanism for operating the hook carrying bar.

Fig. 6 is a detailed side elevation of a part of the rack and pinion operating cam shown in the lower part of Fig. 1, but on an enlarged scale.

Fig. 7 is a rear elevation of the structure shown in Fig. 6.

Fig. 8 is a composite view showing in perspective parts of the cam mechanism shown in Fig. 4, and

Figs. 9 and 10 are diagrammatic views showing the sheds of the two webs in two different positions.

Much of the structure utilized in my present invention has already been set forth in my prior Patents Nos. 2,025,866 and 2,082,890, and also in my co-pending application Serial No. 396,274 filed June 2, 1941, now Patent No. 2,319,863. These patents and the application may be referred to for certain structures not fully described hereinafter and the following description will be confined to the improvements representing my present invention together with such reference to other loom parts as is deemed necessary.

Referring to Fig. 1, I have shown a loom frame 10 having a fixed breast beam 11 and a lay 12 with a reed R rocking backwardly and forwardly about an axis 13. The top shaft 14 of the loom may operate through connections designated generally at 15 to cause reciprocation of the lay and may be geared in any approved manner to the bottom shaft 16. The latter shaft preferably completes one revolution every other pick of the loom and has mounted thereon certain of the mechanism which operates a part of my invention.

Secured to the bottom shaft 16 is a disk 20 on which is mounted for angular adjustment a cam 21 which is shown in detail in Figs. 6 and 7. Cam 21 has a web 22 bolted to the disk and having concentric inner walls 23 and outer walls 24. Opposite sides of the cam are provided with runs 25 formed by inner and outer walls 26 and 27, respectively, which communicate with the concentric run 28 extending between the walls 23 and 24. In order that the crossing of the ladder forming warps may occur on any pick of the loom the cam is provided with two of the runs 25 on opposite sides of the shaft 16. Since the runs and associated parts are the same I will describe the one at the left of shaft 16 as seen in Fig. 1.

Run 25 has associated therewith upper and lower switches 29 and 30, respectively, mounted on pivot pins 31 extending through the web 22. The switch has an inner surface 32 which assists in forming the circular path 28 when the switch

is in its normal full line position shown, for instance, in Fig. 1.

A lever 35 is pivoted as at 36 to the loomside and has its rear end provided with a roll 37 which moves in the runs 25 and 28. When the switches are in their normal positions the bottom shaft turns without causing rocking of the lever 35, but when switch 30 moves to the dotted line position shown in Fig. 6 the roll then passes from the run 28 into the run 25 as the cam turns in the direction of arrow a. Movement of the roll 37 in the non-concentric run 25 causes lever 35 to rock first in a clockwise and then in a counter-clockwise direction as viewed in Fig. 1, causing the forward end of the lever first to rise and then to fall to normal position.

The mechanism for determining when switch 30 shall move from its normal position is set forth in Fig. 7, wherein it will be seen that a lever 40 is secured to a stub shaft 41 rotatable on a carrier 42 through which the shaft 16 extends. The carrier is held by a bolt and slot connection 43 in adjusted angular fixed position on a bracket 44 secured to the loom frame. Secured to the stub shaft 41 is an arm 45 the lower end of which as seen in Fig. 7 is provided with a shoe 46. A spring 47 normally holds the shoe 46 at one side of the path of a stud 50 secured to a lever 51 fastened to the pivot pin 31 of switch 30. A light tension spring 52 normally holds the stud 50 in the position shown in Fig. 7 and also holds the switch 30 in the full line position shown in Fig. 6 to cause roll 37 to move in a circular path. A flexible connector 54 is attached to the upper end of lever 40 and when this connector 54 is raised lever 40 is rocked around its axis against the action of spring 47 to move the shoe 46 into the path of stud 50. This action occurs prior to arrival of the stud to the position shown in Fig. 7 as the cam rotates. Further rotation of the cam moves the small lever 51 angularly in a right hand direction as viewed in Fig. 7 relatively to the cam and causes shifting of the switch 30 from the full to the dotted line position of Fig. 6. It is in this way that the roll 37 is caused to leave the circular path 38 and enter the path 25.

The upper end of connector 54 leads to a pattern mechanism designated herein generally at K. It is not deemed necessary to describe the details of this mechanism and it is thought sufficient to state that on those picks when ladder crossings are to be produced the mechanism K operates to raise connector 54 in time to permit engagement of shoe 46 by stud 50. The mechanism K has leading therefrom a second connector 55 which leads to a measuring mechanism for the crossing warps designated generally at M. Leading upwardly from mechanism M is a system of links 57 connected as at 58 to a lever 59 secured to a rock shaft 60. Arms 61 depending from and secured to shaft 60 carry a bar 62 under which extend the crossing warps designated generally at C. When the loom is to have a ladder bar forming operation the mechanism K will control the mechanism M, Fig. 1, and the latter in turn will operate through linkage 57 to rock shaft 60 and move the bar 62 forwardly, or to the left as viewed in Fig. 1, to supply the length of yarn of the cross warp C needed to pass from one to the other of the two webs being woven and to be described hereinafter.

As shown in Figs. 9 and 10 I set forth diagrammatically the relation between the various warp threads, the two webs of the ladder tape, and the advancer for the cross warps. The top and

bottom fabrics F and F¹, respectively, are formed principally from ground warps defining two sheds, one shed for each fabric. The upper fabric F connects to warp threads W¹ and W² which define the upper shed for top shuttle S¹, while fabric F¹ is connected to warp threads W³ and W⁴ which form the lower shed to receive shuttle S². The warp threads connect with their respective fabrics at the fells e and the top and bottom sheds always occupy substantially the positions as shown in Figs. 9 and 10 when the shuttles are active. The cross warps C are in two groups, one shown at C¹ for the top web and the other at C² for the bottom web, and each group will be woven into the corresponding fabric on non-crossing beats of the loom. On crossing beats, however, the crossing warp C¹ from the top fabric will extend downwardly and rearwardly below warps W² into the lower shed, while the cross warps C² will rise and extend rearwardly to a position above warp W³ and into the upper shed. The two crossing warp groups will cross each other at b at a point considerably behind the fells e. It will be seen particularly from Fig. 9 that the upper shuttle for instance passes through a shed formed by warps W² and the cross warps C² so that the weft which the shuttle lays will extend from the point d forwardly to the upper fell e. Similarly, the lower shuttle passes through a shed formed by warps W³ and the lowered cross warps C¹ and its weft extends from point d' forwardly to the lower fell. Unless provision is made for advancing the points d and d' objectionable loops will be formed on the selvages of the webs F and F¹.

The matter thus far described of itself forms no part of my present invention except as pointed out hereinafter and may be made as set forth in the previously mentioned patents and co-pending application.

In carrying my invention into effect I provide means for advancing the cross warps C and C' from their position shown in Fig. 9 to cause points d and d' to approach or coincide with the fells e. A shaft 70 is rotatably mounted in bearings 71 on the breast beam 11 and has secured thereto a pinion 72 which meshes with a vertical rack 73 secured to the upper end of a rod 74 the lower end of which is attached as at 75 to the lever 35. The rack is in front of the pinion and is guided by the adjacent bearing 71 to cause rotation of shaft 70 in a clockwise direction as viewed in Fig. 1 when roll 37 enters run 25 and cause counter-clockwise rotation of the pinion after the roll has passed the high point of run 25 and approaches a circular run 28.

A bar 80 extends parallel to and behind the shaft 70 and has secured thereto forwardly extending rack bars 81 which are slidably mounted in bearings 82 secured to the breast beam 11. Each rack bar 81 meshes with the top of a pinion 83 secured to the shaft 70. The rear of each rack bar 81 may be secured to the bar 80 by means of a casting 84 fixed to the bar and also to the rack. The bars 81 support the bar 80 when the latter is moved backwardly and forwardly and are also the means by which the latter motions are communicated to the bar 80.

It is to be understood that the loom to which my invention is applied will be capable of weaving several ladder tapes as is customary in narrow ware looms, but in the present instance I set forth mechanism for weaving but one ladder tape. Projecting rearwardly from the breast beam and secured thereto is a guide 86 forked at its rear end to provide a horizontal slot 87

through which the webs F and F¹ pass. A crossing warp finger or hook 88 has the rear bent end 89 thereof proportioned to move forwardly in the slot 87 from a position behind point b shown in Fig. 9. The hook 88 is secured to a small lever 90 pivoted as at 91 to the cross bar. A light tension spring 92 between the bar and the lever 90 tends normally to move the latter to the left so that the hook and guide will ordinarily be in the position shown in Fig. 2. Extending along the bar 80 are spaced parallel front and back rods 95 and 96, respectively, which are pivoted as at 97 to the front and back ends of the lever 90. The right ends of rods 95 and 96 are pivoted as at 100 and 101, respectively, to a lever 102 pivoted as at 103 on the bar 80. Lever 102 projects rearwardly and has mounted thereon a roll 105 which is normally in the position of Fig. 2 at the front of a cam slot 106. The latter extends rearwardly and to the right as at 107 and then rearwardly as at 108 and then rearwardly and to the left as at 109.

The slot 106 is defined by right and left walls 110 and 111, respectively. Wall 110 hangs downwardly from a plate 112 secured to the breast beam 11 by means of a bolt 113 which passes through a saddle 115 bolted as at 117 to the breast beam. Bolt 113 passes through a backwardly and forwardly extending slot 118 in the plate 112 which affords adjustment of slot 106 toward and from roll 105. A rib 120 on the lower forward face of plate 112, see Fig. 8, fits into a groove 121 in the saddle and serves to position the plate 112 and hold the same in fixed position as shown in Figs. 2 and 3.

The wall 111 is formed on a pivot tongue 125 the forward part of which has a bearing 126 to receive a pin 127 mounted in depending lugs 128 on the bottom of plate 112. The tongue 125 fits in a slot 130 extending rearwardly in plate 112 and a rear supporting lug 131 on the tongue overhangs the plate 112 at the end of the slot 130 to hold the tongue normally in the down position shown in full lines in Fig. 4. The wall 111 is formed as part of a head 135 on the underside 45 of the tongue and the rear part of the head has a forwardly and downwardly inclined surface 136. A shock absorbing cushion 140 carried by the breast beam is positioned for engagement with the bar 80 when the latter reaches its extreme 50 forward position.

Under normal conditions when the loom is weaving between cross or ladder bars of the cross warps the parts will be in the position shown in Fig. 2 and lever 35 will be stationary with the switch 30 in position to cause the roll 37 to move in a circular path. When the mechanism K determines that the crossing warps C shall assume the position shown in Fig. 9 for the purpose of forming a ladder bar L, the switch 30 will be 55 thrown to the dotted line position of Fig. 6 as already described, whereupon rod 74 will rise to cause rotation of shaft 70 and rearward movement of the rack bars 81 and bar 80. The start 60 of the rearward motion of the bar 80 will ordinarily occur when the lay is at front center and when the roll 105 is at the forward end of slot 106. As the bar 80 moves rearwardly the roll 105 moves along part 101 of the slot 106, thereby rocking lever 102 to the right, see Fig. 3 to cause rods 95 and 96 to move, respectively, to the left and right to rock lever 90 from the position of Fig. 2 to the full line position of Fig. 3.

As the bar 80 continues to move rearwardly the roll 105 slides through the straight section 108

of slot 106 to hold the hook 88 in the angular position shown in full lines in Fig. 3 with the left end of the hooked end 89 to the right of the warp threads. As the bar 80 approaches the end of its rearward movement roll 105 is moved to the left by section 109 of slot 106 and lever 90 assumes the position shown in dotted lines in Fig. 3 to cause the end 89 to move into the warp shed defined by the crossed threads C1 and C2 to a position behind point b, Fig. 9.

The run 25 of cam 21 is so proportioned that the bar 80 will reach its rearmost position and hook 88 will be in the dotted line position shown in Fig. 3 when the lay is approximately half way between top and back center positions. At this time the sheds are sufficiently open to permit entry of the hook 89 behind the cross warps. As cam 21 continues to rotate roll 37 moves toward circular run 28 and rod 74 starts to move down, whereupon the bar 80 will begin its forward movement. As soon as roll 105 engages the inclined surface 136 the tongue 125 will be raised and swing around its pivot pin 127 to the dotted line position of Fig. 4, the spring 92 holding the lever 102 and parts connected thereto fixed with respect to bar 80 in the dotted line position shown in Fig. 3 throughout the entire forward motion of the bar 80. After the roll 105 is moved to a position in front of the head 135 the tongue falls to its normal position. The forward motion of the bar and therefore of the hook 88 is completed while the lay is still some distance from front center but on its forward beat. I preferably complete the forward motion of the hook when the lay is about at bottom center position.

Upon completion of forward motion of the bar 80 the warp threads and the crossing warp hook will be in some such position as set forth diagrammatically in Fig. 10. In that figure it will be seen that the hook end 89 has moved to a position in front of the fells e and has caused the cross warps C1 and C2 to lie near the warp threads W4 and W1, respectively. Thus, the group of threads C1 from the top web F extend downwardly and forwardly from their corresponding fell e, in front of the hooked end 89 and then downwardly and rearwardly along a path which lies close to the fell of the lower fabric F1. The filling or weft thread G can therefore be beaten forwardly to the fell without the formation of loops.

In order that the weft threads G may be under tension to take-up slack in them as points d and d' advance, I preferably time the movement of the shuttles so that the latter are still moving when the hooked end 89 reaches its extreme forward position. Fig. 1 shows shuttle operating racks 145 for manipulating the top and bottom shuttles S1 and S2. These racks are connected to the usual operating mechanism which keeps them in motion preferably until bar 80 returns to its extreme forward position. It is not essential that the movement of the rack bars 145 shall have any precise timing relationship with the bar 80 so long as a pull is exerted by the shuttles on the weft threads G to take up any slackness which might otherwise form loops at the selvage. Thus, the bar 145 may if desired continue its motion after the bar 80 has reached its foremost position, or if desired the rack bars 145 may cease moving shortly before bar 80 is fully forward and reliance may be placed upon the thread tension customarily found in narrow ware shuttles. In any event it will be desirable to provide some means to take up slack in the weft prior to the crossing of the harnesses H. 78

Whatever the method employed for maintaining tension on the weft thread as the hooked end 89 moves forwardly, it is important to complete the movement of the hooked end 89 to its forward position so that point d will lie adjacent to the fells e before the warp sheds are closed sufficiently to resist movement of the weft threads.

Patents Nos. 351,259 and 613,974 may be referred to for shuttles of the type which are provided with weft slack take-ups the effect of which is to create tension in the weft after the shuttles come to rest. My prior Patent No. 1,817,146 may be referred to for a type of mechanism for moving the rack bar 145 to operate the banks of shuttles.

From the foregoing it will be seen that I have provided means for moving the point of crossing of the cross warps C1 and C2 forwardly so that the cross warps will lie close to the fells of the two webs while the warp sheds are open wide enough to permit the weft tension to tighten the weft threads and thus prevent the formation of loops. It will be seen that this result is accomplished by moving the bar 80 rearwardly and forwardly during a period of time substantially less than one pick of the loom, preferably from front center position of the lay to the following bottom center position. It will further be noted that the hook 88 is moved by a mechanism independent of the lay which permits the hook to reach its extreme forward position before the lay reaches front center. More specifically it will be seen that I have provided a rack and pinion system of driving gear for the bar 80 whereby movement of lever 35 connected to the system effects first a rearward and then a forward motion of the hook 88 by means of a cam switch. It is to be understood that the run 25 of the cam 20 is made of such angular length as to cause the movements of the bar 80 already described. Also, the cam which controls the roll 105 has a pivoted tongue which assists in causing rocking of the hook 88 during backward motion of the bar 80 but permits the hook to remain substantially at rest with respect to the bar 80 when the latter is advancing. While I have shown two rods 95 and 96 I do not wish necessarily to be limited to the use of both of them. It will also be seen that I have provided an improved method for the manipulation of the ground and crossing warps wherein the crossing warps are caused to coincide with certain sheets of the ground warp sheds before the latter are closed to permit the weft to be drawn tightly to prevent the formation of loops at the selvage, after which the ground sheds are changed.

This application is a division of my prior application Serial No. 434,920 in which the novel structure set forth hereinbefore is claimed. The present application is restricted to the method of weaving ladder tapes set forth in the preceding description.

Having thus described my invention it will be seen that changes and modifications may be made therein by those skilled in the art without departing from the spirit and scope of the invention and I do not wish to be limited to the details herein disclosed, but, what I claim is:

1. The method of forming cross bars in ladder tape in a loom having two ground sheds one over the other and a set of crossing warps to form the cross bars, said method consisting of the following steps: crossing a group of crossing warps from one ground shed to the other ground shed, passing a weft from the fell of said other shed

through the latter and behind the crossing warps, completing forward movement of the crossing warps to locate them adjacent to the fell of said other shed while the latter is open and thereafter closing said sheds and beating the weft to the corresponding fell.

2. The method of forming cross bars in ladder tape in a loom having two ground sheds one over the other and a set of crossing warps to form the cross bars, said method consisting of the following steps: moving the set of crossing warps from one shed to the other shed, passing weft under tension from the fell of said other shed through the latter and behind the crossing warps, completing forward movement of the crossing warps to cause them to lie along the fell of said other shed prior to beat-up and while said other shed is still open, and thereafter closing said other shed and beating the weft to the fell of said other shed.

3. The method of forming cross bars in ladder tape in a loom having two ground sheds one over the other and a shuttle having weft connected to the fell of one of said sheds and a set of crossing warps to form cross bars, said method consisting of the following steps: moving the set of crossing warps from the other shed to said one shed, moving said shuttle to cause the same to pass through said one shed to lay weft behind the crossing warps, completing forward movement of the crossing warps to cause them to lie along the fell of said one shed while the shuttle is still moving and prior to beat-up and while said one shed is still open, and thereafter closing said one shed

and beating the weft laid by the shuttle to the fell of said one shed.

4. The method of forming cross bars in ladder tape in a loom having two ground sheds one over the other and a shuttle having weft connected to the fell of one of said sheds and a set of crossing warps to form cross bars, said method consisting of the following steps: moving the set of crossing warps from the other shed to said one shed, passing a shuttle through said one shed to lay in the latter the thread connected to the fell of said one shed behind the crossing warps, completing forward movement of the crossing warps to locate them at the fell of said one shed prior to completion of movement of said shuttle while said one shed is open, and thereafter beating the weft against said crossing warps at said fell and closing said one shed.

5. The method of forming cross bars in ladder tape in a loom having two ground sheds one over the other through which shuttles pass to lay weft and a set of crossing warps to form the cross bars, said method consisting of the following steps: moving the set of crossing warps from one shed to the other shed, passing weft under tension from the fell of said other shed through the latter and behind the crossing warps, completing forward movement of the crossing warps to cause them to lie close to the fell of said other shed while the latter is still open, and thereafter beating the weft against said crossing warps at said fell and closing said other shed.

ELBRIDGE R. HOLMES.
